C. K. ERNST

HOISTING APPARATUS

Filed April 27, 1926

UNITED STATES PATENT OFFICE.

CHARLES K. ERNST OF BUFFALO, NEW YORK.

HOISTING APPARATUS.

Application filed April 27, 1926. Serial No. 104,916.

This invention relates to a hoisting apparatus which is more particularly intended for use in areaways, wells or elevator shafts which are arranged in the side walks between the building and the roadway or street adjacent thereto.

The hoisting apparatus which has been in use heretofore for elevating ash barrels and other materials from the basement of the building through the areaway and above the level of the side-walk has usually been provided with a vertically movable mast section upon which a tackle or winch was mounted, whereby the operation of lifting the barrel or other load was effected. Although such a device serves the purpose of elevating the load to a point above the side-walk it was not wholly satisfactory because there still remained the burdensome task on the part of the attendant to lift the ash barrel or other load from the side-walk into the top of the garbage wagon, ash wagon or other conveyance provided for that purpose. Ordinarily an areaway is not sufficiently deep to permit of the employment of a movable mast section as part of the elevating mechanism to secure a sufficient height of mast which will enable the load to be lifted from the basement and deposited into the top of a wagon box.

The purpose of the present invention, therefore, is to provide means which in cooperation with the ordinary elevating and hoisting mechanism will permit of lifting the load sufficiently high above the side-walk so that the same can be readily deposited into the top of the wagon box, which means are capable of folding vertically so that the total height of the same is considerably reduced and permit of storing same within an area-way of normal height.

In the accompanying drawings:—

Figure 1 is a fragmentary vertical section of an areaway showing a hoisting mechanism mounted therein in its operative position and provided with my improvement whereby ash barrels or the like may be lifted through the areaway and above the side-walk a sufficient distance so that the barrel may be lifted into the top of an ash or garbage wagon.

Figure 2 is a similar section showing the hoisting mechanism folded and arranged wholly within the areaway while the same is not in use and the door or closure 9 at the upper end of the areaway is in its lowered or closed position.

Figure 3 is a fragmentary top plan view of an areaway with the cover removed and the hoisting mechanism therein folded into its inoperative position corresponding to that shown in Figure 2.

Figure 4 is a fragmentary side view of the upper part of the hoisting mechanism showing the manner of mounting the boom containing my invention on the upper part of the vertically movable mast section, while the same is in its operative position.

Figure 5 is a similar view showing the boom in its folded or inoperative position.

Figure 6 is a cross section taken on line 6—6, Figure 4.

Similar characters of reference indicate like parts in the several views of the drawings.

The numeral 10 represents an areaway which is arranged in the side-walk between the adjacent wall 11 of a building and the pavement 12 on the roadway.

Within this areaway and adjacent to one corner thereof is arranged a mast which forms part of the apparatus, which mast in its preferred construction comprises a lower fixed or stationary section 13 and an upper vertically movable section 14 which is guided on the lower mast section. Any approved means may be employed for raising and lowering this movable mast section with reference to the companion stationary section but as the same forms no part of the present invention, an extended description of the same is not deemed necessary.

On the upper end of the upper mast section is pivotally mounted a horizontally swinging mast arm 15 which is connected at its inner end by means of a vertical pivot 16 with a bracket 17 on the upper mast section 14. Upon the outer end of this mast arm is mounted a winch which in its general organization comprises a drum 18 pivotally mounted on the arm 15 so as to turn about a horizontal axis, a hoisting line 19 wound upon this drum and hook 8 or similar means arranged at the outer end of this hoisting line for attaching the latter to the barrel or other load which is to be lifted. This drum may be turned either forwardly or backwardly for the purpose of winding and unwinding the hoisting line by means of any suitable form of gearing, that shown in the drawings being of a well-known type which is hand operated.

As the line will hoist the load only as far

as the drum of the winch the same ordinarily would rise only high enough to clear the top of the side-walk and thus necessitate further manual labor in lifting the load, such as a can or barrel of ashes, from the side-walk to the top of a wagon box intended to receive the same.

Means are therefore provided whereby a load, such as an ash car 20, may be raised 10 higher than would be possible by the mast itself and thus permit of easily dumping the contents thereof into the box 21 of an ash wagon arranged on the roadway immediately adjacent to the areaway and the hoisting apparatus.

These additional means or extension devices which give the hoisting apparatus the above mentioned added capacity, are constructed as follows:

20 This extension consists generally of a boom composed of a lower section which is capable of folding vertically with reference to the mast, and an upper section which is foldable with reference to the lower boom section and is adapted to carry the hoisting line up to such a point that the load, such as an ash barrel, can be raised high enough for dumping its contents into the wagon box. The lower boom section in the present case 25 preferably is made of elbow-shape and consists of a lower normally horizontal arm 22 which is pivoted at its inner end by means of a pin 23 to a base 24 on the upper side of the mast arm 15, and an upper normally upright arm 25 projecting upwardly from the outer end of the lower arm 22 and at an acute angle relatively thereto. The lower mast section may be retained in this normal or operative position by a fastening device 30 of any suitable character but preferably by means of a locking pin 26 passing through corresponding openings 27 and 28 in parts of the lower arm 22 and the base 24, as shown in Figures 1, 3 and 4.

45 The upper section of the boom comprises a normally upright arm 29 which is pivoted at its lower end by means of a horizontal pin 30 to the upper end of the upper arm 25 of the lower boom section, and a normally horizontal arm 31 projecting forwardly from the upper end of the upper arm section 29.

The base 24, the lower boom section and the upper boom section are each preferably made up of two members of angle iron arranged side by side and made of the proper form. Each of the boom sections has its angle iron members connected with each other so that in effect they produce an integral structure, this connection being effected, for example, by means of cross rods or tie bolts as shown at 32 with reference to the lower boom section in Figure 1.

60 The upper boom section may be held in its normal operative position with reference to the lower boom section so as to form an

upward extension of the latter, or this upper boom section may be held in a folded position with reference to the lower boom section so as to produce a compact structure and permit storing of the same in the areaway when the hoisting mechanism is in its lowered position. The locking device which has been found satisfactory for this purpose consists of a locking pin 33 adapted to engage with corresponding openings 34 and 35 in the lower and upper boom sections when the boom is in its operative position, as shown in Figures 1, 4 and 6, and the same pin may also be engaged with corresponding openings 34 and 36 in the lower and upper boom sections for the purpose of holding the two boom sections in their folded positions relatively to each other, as shown in Figures 2 and 5.

On the free or outer end of the arm 85 of the upper boom section the same has pivotally mounted thereon a guide pulley, or sheave 37 over which the free end of the hoisting line 19 is adapted to run so that the load which is attached to the hook 8 thereof 90 may be hoisted an added height equal to the distance which the hoisting sheave 37 is arranged above the hoisting drum 18.

Preparatory to beginning the operation of hoisting loads of material from the base- 95 ment and through the areaway to the wagon on the road-side, the upper mast section is raised to its highest position, the lower boom section is swung from its pendant position, shown in Figures 2 and 5, into its upwardly 100 projecting position, as shown in Figure 4 and locked thereat by means of the pin 36, and the upper boom section is swung upwardly relatively to the lower boom section and locked in this position by means of the 105 locking pin 33, as shown in Figure 4. The boom as a whole is now swung inwardly so that the hoisting pulley 37 is over the area- 110 way, as indicated in Figure 3, at which time the hoisting tackle may be operated for lift- 115 ing the load, such as a can of ashes, through the areaway and up to a point immediately below the upper hoisting pulley 37. After the load reaches this position the boom sec- 120 tions together with the mast arm 15 and the hoisting tackle may then be swung outwardly upon the pivot 16 as an axis so as to carry the ash can or other load from a point over the areaway to a point adjacent to the wagon box. While in this position the can 125 suspended by the hoisting tackle may be readily turned by the attendant into the position shown by dotted line in Figure 1, whereby the contents of the can may be dis- charged into the open top of the wagon box. Thereafter the boom and associated parts may be again swung from a position in which it over-hangs the pavement or curb, to a position in which same over-hangs the areaway and the tackle may be again low- 130

ered for hoisting the next load. The boom therefore operates in the manner of a davit on ship board, whereby life-boats are first lifted from the deck of a ship and then swung laterally away from the ship's side to permit of lowering the life-boat into the water.

After the hoisting apparatus has been thus employed the upper boom section may be 10 again folded relatively to the lower boom section and locked thereto, and the two boom sections may be swung downwardly along side the upper mast section in which position the boom sections are maintained by 15 gravity, inasmuch as the reverse side of the arm 22 at this time rests on top the base 24 and the elbow or angle of the lower boom section overhangs and clears the hoisting drum and associated parts. While the boom 20 is thus folded into its inoperative position, the upper mast section may be lowered and when the same is arranged in its lowermost position the entire hoisting mechanism is below the top of the areaway so as to permit 25 the door 9 to be closed.

By means of this boom extension on the mast of the hoisting mechanism it is possible to hoist freight through the areaway easily and expeditiously and with a minimum expenditure of manual labor, thereby 30 materially reducing the cost of doing this work and also rendering the same more agreeable. Moreover the rapidity whereby ash cans and the like can be thus elevated 35 and emptied into the ash wagon reduces the time in which such wagons are retained in the road-way and therefore avoids unnecessary obstruction of the high-way. Furthermore, this apparatus is composed of comparatively few parts all of which are strong 40 and durable and not liable to get out of order and therefore reduces the cost of maintenance to a minimum.

I claim as my invention:—

1. A hoisting apparatus having a mast, a boom having an elbow shaped inner section provided with a normally horizontal base pivotally mounted at one end on said mast and an arm normally extending upwardly from 45 the opposite end of said base at an acute angle relative thereto, and means for fas-

tening said boom while in its normal position against turning vertically on said mast.

2. A hoisting apparatus comprising a mast having a vertically movable section and a boom provided with an elbow shaped section having a horizontal base pivotally mounted at one end on said mast section, so as to be capable of swinging vertically thereon and an arm extending at an acute angle 60 from the opposite end of said base.

3. A hoisting apparatus comprising a mast having a vertically movable section, a boom provided with an elbow shaped section having a horizontal base pivotally mounted 65 at one end on said mast section so as to be capable of swinging vertically thereon and an arm extending at an acute angle from the opposite end of said base, and means for fastening said boom section in its operative 70 position on said mast section.

4. A hoisting apparatus comprising a mast, a boom having an inner foldable elbow-shaped section and an outer foldable extension section, said elbow-section consisting of a normally horizontal base pivotally connected at one end with said mast and an arm normally projecting upwardly from the opposite end of said base at an acute angle relative thereto and said extension section being foldable vertically relatively to 80 said elbow section.

5. A hoisting apparatus comprising a mast, a boom having an inner foldable elbow-shaped section and an outer foldable extension section, said elbow section consisting of a normally horizontal base pivotally connected at one end with said mast and an arm normally projecting upwardly from the opposite end of said base at an acute angle 85 relative thereto, and said extension section having a lower upright arm which is pivotally connected with the arm of said elbow section and has an upper over-hanging horizontal arm, means for fastening said inner boom section in its normal position, and means for fastening said outer boom section 90 in its folded and unfolded position.

In testimony whereof I hereby affix my signature.

CHARLES K. ERNST.
